(57) **CLAIM**

The ornamental design for a photon LED mask and controller unit in combination, as shown and described.

DESCRIPTION

FIG. 1 is a front perspective view of a photon LED mask and controller unit in combination;

FIG. 2 is a rear perspective view of the photon LED mask and controller unit in combination of FIG. 1;

FIG. 3 is a front elevation view of a photon LED mask of the photon LED mask and controller unit in combination;

FIG. 4 is a rear elevation view thereof;

FIG. 5 is a left elevation view of thereof;

FIG. 6 is a right elevation view thereof;

FIG. 7 is a top plan view thereof;

FIG. 8 is a bottom plan view thereof;

FIG. 9 is a front elevation view of the photon LED mask showing a vertical cross-section indicated as **10-10**;

FIG. 10 is a right elevation cross-sectional view along lines **10-10** of FIG. 9;

FIG. 11 is an enlarged view of the circled section of FIG. 10;

FIG. 12 is a bottom plan view of the photon LED mask of the photon LED mask and controller unit in combination showing a diagonal cross-section indicated as **13-13**;

FIG. 13 is a rear perspective cross-sectional view taken along lines **13-13** of FIG. 12;

FIG. 14 is a front elevation view of a controller unit of the photon LED mask and controller unit in combination;

FIG. 15 is a rear elevation view thereof;

FIG. 16 is a left elevation view thereof;

FIG. 17 is a right elevation view thereof;

FIG. 18 is a top plan view thereof;

FIG. 19 is a bottom plan view thereof;

FIG. 20 is a front perspective view thereof; and,

FIG. 21 is a rear perspective view thereof.

The broken lines illustrate portions of the photon LED mask and controller unit in combination that form no part of the claimed design.
